UNITED STATES PATENT OFFICE.

CHARLES M. SMITH AND ALBERT SMYTH, OF BROOKLYN, NEW YORK.

BINDING.

SPECIFICATION forming part of Letters Patent No. 719,154, dated January 27, 1903.

Application filed October 7, 1901. Serial No. 77,931. (No model.)

To all whom it may concern:

Be it known that we, CHARLES M. SMITH and ALBERT SMYTH, citizens of the United States, residing at Brooklyn, in the county of 5 Kings and State of New York, have invented a new and useful Improvement in Book-binding, of which the following is a specification.

Our invention relates to bookbindings generally, but particularly to the soft flexible bindings of leather and like material used on what are known as "divinity-circuit" books and other books of high grade and finish.

The invention consists in the features of 15 construction and arrangement of parts hereinafter described and claimed specifically.

In the accompanying drawings, Figure 1 is a view of the inside of our completed cover before application to the book, partly broken 20 away; Fig. 2, a view of the cover as applied to a forwarded book. Figs. 3, 4, and 5 represent diagrammatically and in detail the application of our improvements to a forwarded book. Figs. 6 and 7 illustrate the 25 old form of binding "lined to square." Figs. 8 and 9 illustrate the old form of binding "lined to edge."

In order to clearly illustrate and define the scope of our invention, it will be necessary to 30 refer briefly to the prior state of the art.

Books are usually bound in one of two styles, known technically as "lined to square" or "lined to edge." In the first and cheaper style—lined to square—the cover (or case) is 35 first glued to the back of the book and then pasted or glued to the sides or end linings of the book, said end linings being also pasted to the first and last "signatures" or sections of the book, as indicated diagrammatically in 40 Figs. 6 and 7, in which B represents the forwarded book, b b the outer pages of the last sections or signatures, e e the end linings, and C the cover. In the other and more expensive style of binding—lined to edge—the 45 cover or case C is usually made in five pieces—namely, the outer cover C', the two side cover-linings c c, formed with the loose laps c' c', and the two connecting-pieces c² c² at the head and tail of the cover. After making 50 this style of cover it is first glued over the back of the forwarded book, the laps c' c' are

pasted or glued to the sides of the book, and single end linings e e are then pasted over the laps c' c', as will be understood by Fig. 9 of the drawings. In either style of binding 55 the pull of the cover during use on the first and last signatures of the book is sufficient to break the papers at the first and last pages. To overcome this difficulty, the first and last signatures have been "whip-stitched," so as 60 to insure the individual pages against undue strain; but this does not overcome the difficulty, but merely transfers the fault farther toward the center of the book, so that the inner sections are disturbed or ruptured. We 65 obviate this difficulty and relieve all the signatures entirely of undue strain by attaching both the book end linings and the cover itself directly and solely to the "round" of the forwarded book between the joints, as 70 hereinafter described and claimed specifically. Incidentally we have also made a finished cover having the appearance of a lined-to-edge cover by the use of two pieces only—namely, the outer covering and an inner 75 lining.

By reference to Fig. 8 of the drawings it will be seen that the lined-to-edge-cover edge c³ of the outer covering C' overlaps the edges of the cover-linings c c, which is an expensive construction, since it is necessary to first turn said edges in over a piece of zinc with the lining underneath and then carefully cut and trim the edge with a knife, the zinc being then withdrawn with the surplus leather 85 and the trimmed edge being secured to the lining.

In our improved construction of cover the edges c² of the outer lining are turned over, are covered by the edges of the single-piece 90 cover-lining c², as indicated in Fig. 1, giving a neat finished appearance in all respects like the so-called "lined-to-edge" cover, but much simpler and cheaper of manufacture and more durable. In order to insure a 95 stronger union between the finished cover and the round b' of the book when the two are glued together, we prefer to remove a portion of the lining coinciding in position with said round b' of the book and insert in lieu 100 thereof, securely fastened to the inner surface of the outer covering C', a reinforcing-

strip S of woven fabric, such as crash or other fibrous material. This makes a strong hinge or back, which distributes the strain evenly to all the signatures or sections composing the book alike, and since the union between cover and book is confined to the round b' between the joints b^2 b^2 the book end linings and the leaves of the book are entirely free from strain. After the book B is forwarded single book-fly or end linings e e are secured to the round b' of the back beyond the joints b^2 b^2 , as shown in Fig. 4, and the completed cover C is then secured to the round b' of the book between the joints b^2 b^2 , as before mentioned. A book thus formed is rendered much more lasting and durable, its integrity also insured and maintained without in the least increasing its cost of production when compared even with the lined-to-square binding. As compared with the old form of lined-to-edge binding it is much cheaper.

What we claim as our invention, and desire to secure by Letters Patent, is—

1. In combination with a forwarded book, a cover consisting of an outer covering the edges of which are turned in and covered by the edges of a cover-lining, together with said cover-lining having its central portion coinciding with the round of the book removed and replaced by an insertion of woven fibrous material, for the purpose and substantially in the manner described.

2. The combination with a forwarded book and end linings overlapping the joints of said book, of a finished cover secured to said book at the round of the back between the joints for the purpose and substantially in the manner set forth.

CHARLES M. SMITH.
ALBERT SMYTH.
